METHOD FOR MAKING STEMS FOR TIPLESS LAMPS

Filed May 27, 1921

FIG.1. FIG.2. FIG.3.

INVENTOR
JOHN J. HIGGINS

BY
J. J. Higgins
ATTORNEY

UNITED STATES PATENT OFFICE.

JOHN JOSEPH HIGGINS, OF EAST ORANGE, NEW JERSEY, ASSIGNOR TO WESTINGHOUSE LAMP COMPANY, A CORPORATION OF PENNSYLVANIA.

METHOD FOR MAKING STEMS FOR TIPLESS LAMPS.

Application filed May 27, 1921. Serial No. 473,024.

To all whom it may concern:

Be it known that I, JOHN JOSEPH HIGGINS, a citizen of the United States, and a resident of East Orange, in the county of Essex and 5 State of New Jersey, have invented a new and useful Improvement in Methods for Making Stems for Tipless Lamps, of which the following is a specification.

This invention relates to a method of 10 manufacturing stems for incandescent electric lamps of the tipless type.

An object of the invention is the provision of a novel method of so joining together the several parts which constitute a lamp stem 15 as to materially reduce such difficulties as cracking and breaking thereof.

Another object is the formation of the several parts to be combined to form a unit structure so that the surfaces at the junc- 20 tures of the several parts shall be curved, thus eliminating sharp angles which are undesirable in the glass-working industry.

Other objects of the invention will be ap- 25 parent from the following description.

In the manufacture of incandescent lamps of the so-called tipless type, it has been the custom to join an exhaust tube with the stem or flare tube in order to facilitate the exhausting of the lamp bulbs. Considerable 30 difficulties are encountered in performing this operation; the main difficulties of cracking and breaking being apparently due to excessive strains set up during the sealing together of the several parts of the stem 35 to form a unit structure. Such defects increase the cost of manufacturing operations to an unwarranted extent. The invention hereinafter set forth is directed to a method of so joining together the several parts of a tipless lamp stem as to avoid the difficulties above mentioned.

The drawings accompanying this speci- 40 fication illustrate the condition of a stem at various stages of manufacture, and, in these drawings,

Fig. 1 is a view, partially in section, of the assembly of the various parts constituting a stem;

Fig. 2 is a view, partially in section, of the parts after being joined;

Fig. 3 is a sectional view of the stem showing the curved surfaces at the junctures of

the several parts and showing an air-exhaust passageway.

Fig. 4 is a side elevational view of the 55 stem showing, in outline, the exhaust tube and the passageway.

The description of the method will be set forth in connection with the formation of a tipless lamp stem wherein an exhaust tube 60 is joined in the press or seal and this tube is preferably positioned concentrically in the flare tube. The press also includes the ends of the flare tube, the arbor and the leading-in conductors. The stem formed by 65 this method provides for the step of drawing or pulling some part of the stem while the glass in the joint or seal is in molten condition. This drawing of the glass per- 70 mits the quantity of glass at the press to be somewhat reduced and provides for the formation of curved surfaces at the junction of any two of the parts.

Referring particularly to the drawings, 75 Fig. 1 illustrates the several individual parts of a stem assembled and ready for heating by any desirable source of heat such, for instance, as the well known pointed fires (not shown). The several well known parts comprising a stem are, a tube 1 having a flared 80 portion 2, an arbor 3 for supporting the filament, leading-in conductors 4 and an ex- 85 haust tube 5 provided with a constricted portion 6 for tipping off after the lamp bulb has been exhausted. These several 90 parts are preferably assembled in over- 95 lapped position, as illustrated in Fig. 1.

After the parts have been assembled in a stem-making machine, preferably in the relation shown, and the fires have been ap- 90 plied to heat the ends or overlapped portions to a molten condition, the parts are pressed together in any suitable manner in order to form the stem. The shape of the joint or press may have any desired con- 95 tour, according to the form of the press jaws employed. In this embodiment, the press preferably is formed in the shape of an ellipse which may be readily appreciated by reference to Figs. 2 and 4. It is to be noted that the surfaces 7 at the juncture of the flare tube and the exhaust tube are sharp and form an acute angle, as illustrated in Fig. 2; also that the surfaces 8 at the junc- 100

ture of the arbor with the end of the press also form sharp angles.

The next step in performing the method is to reposition or stretch the glass at the joint or press. This step permits the section of the glass at the press to be made more uniform and to reduce the amount of glass in the press itself. This repositioning or stretching may be performed in any desired manner, however, for the convenience of manufacture, it is desirable to draw or pull the exhaust tube. Such a drawing or pulling permits a certain amount of the glass to be withdrawn from the press and also provides for the formation of curved surfaces at the juncture of any two of the parts comprising the stem.

The results of the drawing operation are illustrated in Fig. 3 where the amount of glass in the sealed portion proper has been reduced by drawing the exhaust tube upward and has carried part of the glass of the press therewith and, in addition, the surface at the juncture of the flare and exhaust tubes is curved, as illustrated at 9, and the surface at the juncture of the arbor with the lower portion of the press is curved as illustrated at 10. It is to be noted that a constriction 11 has been formed in the lower end of the exhaust tube but this is not detrimental so long as the opening in the exhaust tube is not closed.

After the step of stretching or pulling has been completed, compressed air is admitted to the exhaust tube and the glass at the press, being still in a plastic condition, is forced aside and an opening or passageway 12 leading from the exhaust tube, is formed in this press or joint as illustrated in Figs. 3 and 4. This opening provides the passageway for the air drawn from the lamp bulb to the exhaust pump during the operation of exhausting the lamps.

By forming the stem in accordance with this method, the glass forming the stem is drawn to provide a more uniform cross-section at the press or seal and provides for curved surfaces between any two of the parts comprising the stem, and the utilization of this method has been of distinctive advantage in substantially avoiding the cracking and breaking difficulties which have been experienced in the manufacture of stems by other methods.

This method, although described in connection with the formation of a particular article, is not to be considered as being limited to this particular use but may be employed to manufacture other articles of a similar nature.

What is claimed is:

1. The method of forming a stem for an incandescent lamp which consists in assembling individual glass parts, heating and pressing together the said parts, effecting a

relative bodily movement of said parts to reduce the amount of glass in the seal and to alter the surface contour thereof.

2. The method of forming a stem for an incandescent lamp which consists in assembling individual glass parts including an exhaust tube, heating and pressing together to unite portions of said parts, working the glass to provide rounded surfaces at the union of said parts and then forcing air down one of said parts to provide a passage in said union.

3. The method of forming a stem which consists in assembling individual glass parts, heating and pressing portions of said parts together, working the glass to form curved surfaces at the juncture of the parts and forming a passage through the compressed portion.

4. The method of forming the stem of an incandescent lamp which consists in assembling the component parts of the stem, locally heating said parts, pressing the heated portions to unite the parts, changing the relative positions of the parts to work the heated portion while still plastic and in forming a passage through the union of said parts.

5. The method of forming a stem for an incandescent lamp which consists in assembling a flare and an exhaust tube, an arbor and leading-in conductors, heating and pressing together predetermined portions of the named parts, pulling said exhaust tube and admitting compressed air therethrough to form a passage way through the pressed portions.

6. The method of forming a stem for an incandescent lamp which consists in assembling, in overlapped position, the ends of an exhaust and a flare stem tube, an arbor and leading-in conductors, heating the overlapped portions of said named parts, pressing the same into integral relation, pulling said exhaust tube to remove some of the glass from the formed press and blowing an opening in said press by introducing air, under compression, into said exhaust tube.

7. An incandescent electric lamp stem comprising an exhaust tube, a flare tube and an arbor united at their ends in a common mass and having a constricted portion at a point adjacent to the mass.

8. An incandescent electric lamp stem comprising an exhaust tube, a flare tube and an arbor fused together in a common mass, the exhaust tube having its diametrical dimension reduced at a portion of its length adjacent to the seal.

9. An incandescent electric lamp stem comprising an exhaust tube, a flare tube and an arbor united in a common mass, the exhaust tube having a relatively small amount of material in a portion of its length adjacent to the mass.

10. A stem for an electrical device comprising an exhaust tube and a flare tube united at their ends in a mass and having a constricted portion at a point adjacent to the mass.

11. In an electrical device, a stem comprising a flare tube and an exhaust tube therein, the walls of said tube being integrally connected by a union having a chamber blown

therein communicating with said exhaust tube, another aperture in the wall of said chamber and a constricted portion in said exhaust tube adjacent said chamber.

In testimony whereof, I have hereunto subscribed my name this 25th day of May 15 1921.

JOHN JOSEPH HIGGINS.
